UNITED STATES PATENT OFFICE

2,106,155

CONCENTRATOR

Alexander C. Munro, Britannia Beach,
British Columbia, Canada

Application July 1, 1936, Serial No. 88,398

7 Claims. (Cl. 209—18)

This invention relates to an ore concentrating apparatus and pertains particularly to a combined classifying and flotation apparatus useful in the recovery of minerals or the like by froth flotation.

This application is a continuation-in-part of my two co-pending applications, Serial Nos. 15,041, filed April 6, 1935, and 22,503, filed May 21, 1935.

10 The principal object of the invention is to provide an apparatus of the character described having a low installation cost, long life, a low up-keep cost, and a lower power consumption than commercially available forms of apparatus 15 of comparable utility.

15 A further object of the invention is to provide an apparatus provided with aerating agitator means and adapted to function as a classifying apparatus wherein certain described aeration features are obtained co-incidentally and in cooperation with a classifying operation.

20 A further object of the invention is to provide an apparatus in which an ore pulp or the like, comprising a liquid suspension containing mixed 25 relatively coarse and relatively fine solid particles, together with solid mineral particles which are separable by froth flotation, is subjected to both froth flotation and classifying operations in a single tank, and in which a froth flotation 30 concentrate, a settled coarse fraction, and a fine slimes fraction, are separated from said pulp and separately discharged from said tank.

35 A further object of the invention is to provide means for subjecting a fluid body containing, in suspension, divided mineral particles of a "floatable" nature and particle size range together with fine particles which are not susceptible to froth flotation and also relatively coarse particles which may contain mineral values but which 40 are not susceptible to froth flotation without further size reduction, to an aerating agitation in the production of a froth concentrate containing the principal portion of mineral values of a floatable size, and means co-operating with said 45 agitating means to effect a classifying operation on the un floated material to recover therefrom such relatively coarse particles and to discharge such coarse particles as a separate product and at a point removed from the discharge 50 of residual fine solids or slimes in suspension.

55 Other objects and features of the invention will be brought out in the following description of preferred embodiments thereof, or will be apparent from such description.

The device of the present invention may com-

prise, essentially, a compartment provided with means for maintaining a body of liquid therein, a looped carrier element having a plurality of agitator and elevator elements secured thereto, and having its lower portion mounted for movement through said body of fluid to subject the material therein to agitation and to scoop up and elevate or lift the coarser fraction of said material and discharge the same from the liquid body separate from the finer material in suspension 10 in said body, and agitating means adapted to effect an aerating agitation of said liquid body at a point removed from said carrier element. The apparatus is also provided with separate launder means for removal of a froth flotation 15 concentrate and for removal of liquid containing suspended slimes. Numerous modifications of the apparatus may be made according to the principles herein set forth, examples of which are shown in the attached drawings, and referring thereto:

Fig. 1 is a partly broken away plan view of one form of my concentrating apparatus;

Fig. 2 is a partly broken away side elevation thereof;

Fig. 3 is a vertical section thereof taken on line 3—3 in Fig. 2;

Fig. 4 is an enlarged scale detail of one of the agitator or elevator elements which may be provided according to my invention;

Fig. 5 is a view corresponding to Fig. 3, showing a modified form of apparatus of the general type shown in Figs. 1 to 3;

Fig. 6 is a transverse section of a modified form of apparatus embodying an elevator classifier and flotation means, taken on line 6—6 in Fig. 8;

Fig. 7 is a transverse sectional view of the apparatus taken on line 7—7 in Fig. 6;

Fig. 8 is a horizontal section of the device 40 taken on line 8—8 in Fig. 6;

Fig. 9 is a plan view of another modified form of the invention, the upper portion of the elevator being broken away;

Fig. 10 is a section on line 10—10 in Fig. 9; 45 and

Fig. 11 is a section on line 11—11 in Fig. 9.

Referring to Figs. 1 to 3, the device may comprise a tank 1 provided with a curved bottom wall 2 and end walls 3. The tank 1 may be of 50 substantially any desired shape, but in view of the fact that the present described form of invention provides two adjacent elevator elements, the aforesaid tank is preferably of a rectangular shape. Above the tank 1 I preferably pro-

5

10

15

20

25

30

35

40

45

55

vide a housing 4 within which the elevator classifier assembly may be disposed, said assembly comprising a pair of head pulleys 5 mounted on a shaft 6 provided with suitable driving means such as a gear train 7 and each of said pulleys carrying an endless flexible carrier member 8 provided with a plurality of elevator elements or buckets 9, and looped downwardly from said head pulleys below the level of liquid in said tank, as hereafter more fully described. Any desired number of pulleys 5 and carriers 8 may be provided, said pulleys being preferably mounted on a common shaft, depending upon the classifying capacity desired in the apparatus.

15 As shown in Fig. 4, the buckets 9 may be formed as a bent plate defining an open-ended bucket with the flexible carrier 8 and secured thereto in any suitable manner as through the agency of rivets 11 which are preferably located medially along the height of that portion of the plate which backs against the carrier 8, whereby proper flexure of the carrier member 8 may be obtained at the position of the head pulley. The carriers 8 are moved in the direction indicated by the arrow in Fig. 3 upon clock-wise rotation of the pulleys 5 through the agency of the aforesaid gear train, and the buckets 9 are so arranged on said carriers that the crotches 12 thereof are directed upwardly along the ascending run of said carriers.

The tank 1 is provided with slimes overflow means which, in this embodiment, may comprise an overflow launder 13 extending longitudinally of said tank in the center of an inner zone I defined by the lower portion 14 of the downwardly looped portion of the carriers 8 and extending in the direction of the axis of rotation of the head pulleys 5, the lips of said overflow launder defining a pulp or liquid level within the tank 1 as indicated by the dash line L. The housing 4 is preferably extended below the level L as at 4', and between said downwardly extending portions 4' and the longitudinal or side wall portions 15 of the bottom 2 a suitable aerating agitating means is preferably provided, such as a plurality of drop pipes 16 connected to an air header 17 through which a suitable quantity of air may be delivered to cause formation of a mineral-bearing froth in accordance with conventional froth flotation practice. Suitable baffles are preferably provided within the outer zone O which is defined by the side walls 15 of the tank 1 and the portion 14 of the carrier 8, constituting, in this embodiment, flotation zones at each side of the tank 1 extending parallel to the inner zone I. Such baffles are shown at 18 and 19, and concentrate launders 21 are provided along said side wall portions 15 at a level somewhat above the level L aforesaid, in position to withdraw the produced froth according to common practice.

Suitable means are provided for admitting a pulp containing the comminuted ore or other material to be treated, such as feed launders 22 which may communicate with the tank 1 at the aforesaid flotation zones at any desired position, for example, adjacent one end of said tank. The feed launders 22 preferably enter the tank 1 at a point below the level L.

In the operation of the present described form of the device, a suitable feed of comminuted ore in suspension in water or other suitable fluid is introduced to the tank 1 through the launders 22 (the tank 1 having been previously filled with water to the level L and a suitable flow of air through the drop pipes 16 having been estab-

lished), and the aerating agitation produced by the admission of air at 16 will result in the formation of a froth concentrate at the upper portion of the flotation zones, it being appreciated that the feed will contain a desired quantity of flotation reagent according to common practice. It is well known that at a given rate of agitation with a proper proportion of flotation reagent, mineral particles of a certain size range will be caused to enter the froth and recovered as a concentrate, while particles larger than such size range will not be efficiently collected. Similarly, particles which are smaller than the aforesaid size range will be difficultly collected. For this reason the device of the present invention is highly adapted for efficient metallurgical performance if the feed is not ground too finely at first and is introduced in relatively coarse condition to the flotation zones, the particles which will float recovered in the concentrate, the unfloated particles being then subjected to the classifying operation provided by the flexible carriers 8 and buckets 9 and passed to a further comminuting operation, and the fines, which generally contain no significant proportion of unrecovered values, allowed to escape continuously from the device at slimes overflow launder 13. The oversize particles or sands settle downwardly from the flotation zones and are picked up by the open-ended buckets 9 and carried over the pulleys 5, and suitable water supply means are preferably provided on the downward side of the pulleys 5 to assist in ejection of the collected sands from the bucket crotches 12. Such water supply means may comprise a plurality of valved nozzles 23, positioned to force jets 24 of water against the moving buckets 9, which water, together with the ejected sands, flows downwardly into a sands launder 25 provided along one side of the device adjacent the upper end of the housing 4. A suitable sheet metal cover or the like may be provided as at 26 to enclose the head end of the device, if desired. The slimes are carried away from the pulp body in suspension at the slimes overflow launder 13, which, in this embodiment, is disposed in the relatively quiescent inner zone I, thus affording maximum opportunity for the coarse particles to settle into position to be scooped up by the buckets 9.

The form of apparatus shown in Fig. 5 conforms in general to that shown in Figs. 1 to 3, differing principally with respect to the position of the flotation zone with respect to the classifier structure. Referring thereto, a tank 27 is provided with a curved bottom 28 and a housing 29 extending upwardly from said tank in a manner comparable to the housing 4 above, carrying a pulley 5 mounted on a shaft 6. The pulley 5 carries a flexible carrier 8 provided with buckets 9 after the manner above described, which carrier loops downwardly within the tank 27 to a point 60 adjacent the curved bottom 28. The aerating agitator structure is disposed within the inner zone I' defined by the looped portion 30 of the carrier 8 and may comprise an air header 31 provided with a plurality of drop pipes 32, suitable baffles being provided as at 33 to properly direct the flow of the froth and break up the froth bubbles formed by admission of air at 32. A baffle 34 is preferably provided at one side of the flotation zone to minimize travel of froth outside of the flotation zone and a concentrate launder is provided at 35 for withdrawal of concentrate from said zone. Slimes overflow launders 36 may be provided along the edges of the tank 27 and a suitable sands launder may be provided as at 75

37 in accordance with the showing at 25 above, suitable water jet means being provided as at 38. A sheet metal cover 39 over the head end of the carrier member may also be provided, if desired. It will be understood that any suitable number of pulleys 5 and carrier members 8 may be provided.

The operation of this form of the invention is quite comparable to that described in connection 10 with the showing in Figs. 1 to 3, a suitable feed being introduced through a feed launder which may open into the flotation zone as at 40, flotation effected by admission of air through the pipes 32, and the froth concentrate withdrawn at 35. The 15 unfloated heavy particles pass exterior of the flotation zone at the sides of the carrier 8 into the outer zone O', the oversize sands being removed from the tank by the buckets 9 as above described and discharged into the sands launder 20 37 from whence they may be conducted to a suitable apparatus for effecting further comminution. The suspended slimes are removed from the tank 21 at the overflow launders 36 and may be passed to waste or further treatment in accordance 25 with the particular ore concentrating problem at hand.

In Figs. 6 to 8 I have shown a modification comprising a tank or boot 41 which may be formed with upwardly flaring side walls 42 and may, for 30 example, be square or rectangular in shape. In this form of the device, provision is made for withdrawing the overflow of classified slimes along two opposite sides of the device as at 43 and 44 and for withdrawing froth from the device at the 35 remaining sides as at 45 and 46, as will be more fully described subsequently. The classifying elevator means extends within the boot 41 and may consist of a belt or flexible member 47 mounted on a drum or pulley 48 carried by a shaft 49 40 which is journaled in suitable bearings 51 suitably mounted on a casing 52 which is in turn mounted on or within the tank or boot 41. The belt 47 is provided with open-ended buckets or lifts 53 secured thereto and adapted to operate as 45 agitating and elevating means. The shaft 49 may be driven by any suitable means so as to cause a movement of the belt 47 in the direction indicated by the arrow A. An idler roll or drum 54 may be mounted on the elevator belt 47 at the lower 50 end thereof so as to hold the belt distended at proper curvature and to also hold the belt in substantially vertical position by its weight and prevent lateral deflection by the reaction of the operation of the belt and buckets on the material in 55 the tank. In most cases, however, this idler may be dispensed with, the weight of the buckets on the belt being sufficient to keep said belt in proper position.

The buckets or lifts 53 may be of any suitable 60 size and shape and are preferably formed as a blade or plate extending at an inclination to the elevator belt and secured thereto in any suitable manner as by riveting. The inclination of the plates or buckets is upward and outward on the 65 ascending run of the belt and downward and outward on the descending run of the belt, the buckets being open at each end so as to permit fines to drain from the buckets as the latter ascend from the body of pulp or fluid undergoing 70 treatment. A feed launder or chute 55 is provided for supplying pulp or material to be treated, discharging for example, into the interior of the casing 52 above the level of liquid in the tank 41 but sufficiently far from the elevator classifier 5 means to enable the material so supplied to ef-

fectively gravitate or settle toward the bottom of the tank. The casing 52 is preferably not carried downwardly to the bottom of the tank 41, but terminates as at 56 a short distance below the pulp level which is maintained by the overflow 5 lips 57 along the classifier overflow launders 43 and 44, providing openings below the bottom of the casing to enable the coarser material in the pulp to settle to the bottom of the tank, directly below the elevator classifier and to also enable 10 the finer material to pass outwardly and upwardly to the overflow lips 57. At the upper portion of the casing 52 and on the side thereof which is adjacent the descending run of the elevator classifier, a launder or chute 58 is provided 15 for receiving coarse material from the elevator classifier buckets and conveying the same to any suitable receiving means, to a ball mill or the like, and a deflector or inclined apron 59 is provided adjacent the elevator buckets to guide material 20 discharged from said buckets into said launder 58, in connection therewith suitable water jet means may be provided as at 61 to facilitate complete discharge of material from the buckets.

Within the casing 52, along the axial ends or 25 edges of the belt 47, I provide a distributing plate 62 disposed at an angle to the horizontal, at a level upwardly removed from the pulp level above defined. These baffles are preferably wider at their high side than at their low side and serve 30 to interrupt the free fall of fluid or pulp discharged from the open buckets and distribute the same over the width of the casing 52, such liquid or pulp falling downwardly into the main body of pulp and resulting in the formation of a froth, 35 which flows under suitable baffles 63 disposed parallel to the concentrate launders 45 and 46, which baffles may be formed as continuations of the sides of the casing 52 as in the manner shown at 56. These baffles preferably do not extend to as low a level within the bottom or tank 41 as do the baffles 56, whereby the froth produced in falling from the buckets will preferentially escape under the baffles 63 and thence to the concentrate 45 launders 45 and 46, rather than under the baffles 56 and thence to the classifier launders 43 and 44.

The blades or buckets 53 function in a manner somewhat similar to the blades 9 above. The cascading action of the fluid discharged from 50 the open bucket ends is productive of the desired aeration, and the distributing baffles or plates 62 are placed at such height above the fluid level as to intercept an adequate quantity of material so discharged, and to further aerate 55 while distributing the same laterally with respect to the width of the tank 41, whereby a substantially uniform supply of highly aerated froth is directed to the launders 45 and 46. Furthermore, the descending run of buckets serves to 60 entrain air upon entering the fluid body and to distribute the same into said liquid body, while the lower end of the carrier belt 47 serves to adequately agitate the liquid within said tank.

The form of the invention shown in Figs. 9 65 to 11 comprises a tank 71 which may be rectangular with sloping side walls as shown, said tank having classifier overflow launders 72 extending adjacent the upper edges or lip 73 at two sides thereof and flotation concentrator over- 70 flow launders 74 extending adjacent the upper edges or lips 75 of the tank at the other sides thereof. The feed of pulp is supplied to the tank by a feed chute or launder 76 opening into a vertical casing 77 within which operates the 75

classifying elevator 78 consisting, for example, of a belt 79 running over a driving pulley 81 and provided with inclined buckets 82, suitable discharging means indicated at 83 being provided 5 for receiving material discharged by gravity from the buckets after they pass over the drum at the upper end of the belt. Water jet means 83 are preferably also provided at the head end of the elevator mechanism to assist in the discharge of 10 coarse material from the buckets 82 into discharging means 83. The lower ends of the walls of casing 77 extending down into the tank constitute baffles, the baffle portions 84 which are between the belt 79 and the classifying over- 15 flow lips 73 extending to a lower level than the baffle portions 85 extending between the belt and the froth overflow lips 75.

In order to increase the flotation action of the apparatus, an auxiliary belt or movable member 20 86 is provided, for example, within the classifier belt and carried by a pulley 87, said belt being provided with blades 88 adapted to dip into the upper portion of the body of liquid or pulp in the tank and to produce a frothing action as 25 hereinafter described. Driving means indicated at 89 and 91 are provided for the respective belts 79 and 86, said driving means being adapted to drive the frothing belt 86 at a much higher speed than the classifying belt 79.

30 In the operation of this form of the invention the pulp, which is assumed to contain some frothing agent, is supplied to the tank through the feed chute 76 and the coarser material settles to the bottom of the tank and is eventually ele- 35 vated by the classifying elevator belt 79 and discharged at 83. The flotation belt 86 is operated at sufficient speed to pick up the pulp from the upper portion of the body of liquid in the tank and to carry such pulp over the top of the belt 40 and cause it to cascade into the body of liquid at the descending side of the belt, producing a very effective frothing action. This cascading takes place both from the ends and the outside edges of the flotation belt and results in produc- 45 tion of a body of froth which flows under the lower edge or baffle portion 85 of the vertical casing 77 and over the froth overflow lip indicated at 75 into the froth overflow launders 74 at each end of the tank, the baffles 84 extending 50 below the level of the layer of froth so as to prevent the froth from passing to the classifier overflow launders 72 and directing all the froth into the concentrate launders 74. The fines from the pulp overflow into launders 72, so that the 55 operation of this apparatus effects separate recovery of the flotation concentrates, the fines or slimes, and the coarse material for regrinding. The apparatus may be applied to treatment of mineral-bearing pulp containing residual frothing agent as a result of previous flotation operations, or it may be applied to the treatment of 60 fresh pulp together with added frothing or flotation agent.

I am aware of the fact that previously de- 65 scribed forms of flotation apparatus have been provided with aeration means such as paddle-like beaters in position to act upon the pulp and mechanically or physically inject the pulp into the produced froth. The present-described ap- 70 paratus functions on a materially different principle, in that the pulp is elevated from the main pulp body and allowed to cascade to the upper surface of the pulp body, which cascading causes an aeration of the cascaded portions and an en- 75 trainment of air by the particles as they enter

the pulp body in a manner which is not possible with the beater-type apparatus above referred to. Furthermore, the presence of the flexible carrier, with its agitator and elevator elements, within the main body of pulp provides a constant agitation of the pulp under conditions of at least partial aeration of such pulp body. 5

It will be seen that each of the forms of apparatus above described serves to separate a flotation concentrate, a slimes product, and a coarse 10 product. Each of these products is separately discharged and may be delivered to any suitable point for further treatment or disposition. In general, the slimes product may be discharged to waste, while the coarse product is preferably re- 15 turned for further comminution, after which it may be subjected to a further concentration, either in another apparatus or by returning it to the same concentrating apparatus in closed circuit with the grinding mill or other comminuting 20 apparatus.

Other modifications of the device, for use either as a flotation apparatus or as a simple agitating apparatus, will occur to those skilled in 25 the art, and I in no wise choose to be limited to the specific structures disclosed, but rather to the scope of the appended claims. For example, I may employ one or more chains supported by suitable sprockets mounted on the shaft 6 in Figs. 1 to 3 instead of the belt 8, the blades 9 30 being secured to the chains in any suitable manner. Alternatively, one or more cables may be employed in a manner comparable to the employment of chains, the essential requirement being that the carrier is essentially flexible. Similarly, the rotatable supporting means for the flexible carrier will be selected according to the particular type of flexible carrier employed, a pulley for a belt, a sprocket wheel for a chain, a grooved pulley for a cable, and the like. Other forms of elevator buckets may also be employed, as shown for example in my above-mentioned copending application Ser. No. 15,041. 35

I claim:

1. A concentrator which comprises: a tank provided with means for supplying thereto a pulp containing divided material together with liquid and with froth flotation agent; movable elevator means extending into said tank and comprising an endless flexible carrier having its upper end mounted above said tank on a rotatable supporting means to provide a downwardly looped portion extending within said tank, said looped portion having ascending and descending run portions, and a plurality of open-ended bucket means secured to said flexible carrier, said bucket means being directed upwardly and downwardly respectively on said ascending and descending run portions and adapted to agitate the material in said tank and to scoop up coarse material and lift the same from said tank while allowing liquid to drain therefrom through the open ends thereof and to discharge such coarse material outside of said tank, said downwardly looped portion of said carrier defining with said tank an inner zone and an outer zone extending parallel to the axis of rotation of said supporting means; driving means for said rotatable supporting means; slimes overflow means in one of said zones for maintaining a liquid level in said tank; froth producing means in the other of said zones for producing a froth concentration in said zone; and concentrate overflow means in said other zone for withdrawing the froth so produced. 50

55

60

65

70

75

80

2. The apparatus set forth in claim 1, said one zone comprising said inner zone.
3. The apparatus set forth in claim 1, said one zone comprising said outer zone.
4. A concentrator which comprises: a tank provided with means for supplying thereto a pulp containing divided material together with liquid and with froth flotation agent; movable elevator means extending into said tank and comprising an endless flexible carrier having its upper end mounted above said tank on a rotatable supporting means to provide a downwardly looped portion extending within said tank, said looped portion having ascending and descending run portions, and a plurality of open-ended bucket means secured to said flexible carrier, said bucket means being directed upwardly and downwardly respectively on said ascending and descending run portions and adapted to 10 agitate the material in said tank and to scoop up coarse material and lift the same from said tank while allowing liquid to drain therefrom through the open ends thereof and to discharge such coarse material outside of said tank, said 15 downwardly looped portions of said carrier defining with said tank an inner zone and an outer zone extending parallel to the axis of rotation of said supporting means; driving means for said rotatable supporting means; slimes overflow means in one of said zones for maintaining a 20 liquid level in said tank; air-admitting means in the other of said zones for admitting air into said zone below said liquid level to produce a froth concentration in said zone; and concentrate 25 overflow means in said other zone for withdrawing the froth so produced.
5. The apparatus set forth in claim 4, said one zone comprising said inner zone.
6. The apparatus set forth in claim 4, said one zone comprising said outer zone.
7. A concentrator which comprises: a tank provided with means for supplying thereto a pulp containing divided material together with liquid and with froth flotation agent; movable elevator means extending into said tank and comprising an endless flexible carrier having its upper end mounted above said tank on a rotatable supporting means to provide a downwardly 10 looped portion extending within said tank, said looped portion having ascending and descending run portions, and a plurality of open-ended bucket means secured to said flexible carrier, said bucket means being directed upwardly and downwardly respectively on said ascending and descending run portions and adapted to agitate the material in said tank and to scoop up coarse 15 material and lift the same from said tank while allowing liquid to drain therefrom through the open ends thereof and to discharge such coarse material outside of said tank, said 20 downwardly looped portions of said carrier defining with said tank an inner zone and an outer zone extending parallel to the axis of rotation of said supporting means; driving means for said rotatable supporting means; slimes overflow means in said outer zone for maintaining a liquid level in said tank; mechanical agitating means in said 25 inner zone adjacent and extending below said liquid level; means for operating said mechanical agitating means to produce a froth concentration in said zone; and concentrate overflow means in said inner zone for withdrawing the 30 froth so produced.

ALEXANDER C. MUNRO.
